UNITED STATES PATENT OFFICE

2,494,439

THREAD-CUTTING THIMBLE

Elynor D. Gorka and Minor E. Gideon,
Kansas City, Mo.

Application October 22, 1945, Serial No. 623,642.

6 Claims. (Cl. 7—14.5)

1

This invention relates to thimbles of the character employed to protect the end of the finger when sewing and the primary aim is the provision of a protecting sewing thimble having as a part thereof a unique means for cutting threads without removing the thimble from its operative position on the finger of the wearer.

One of the important aims of this invention is to provide a thread cutting thimble, the cutting element whereof is fully protected against accidental contact and which has a unique protective guard that yields upon application of a thread thereagainst to allow the thread to encounter the cutting edge and thereby be severed.

Specific structural details of the thimble having characteristics above set down constitute very important aims of the invention and include the unique manner of disposing a protecting spring adjacent to the cutting edge of a disc that is held in place beneath a removable cap on the end of the thimble and the form of the said cap, disc and spring, all as will be more fully hereinafter described by reference to the accompanying drawing, wherein:

Fig. 1 is a side elevational view of a thread cutting thimble made pursuant to our invention.

Fig. 2 is a longitudinal central sectional view taken on line II—II of Fig. 1, and

Fig. 3 is a fragmentary top plan view of a portion of the thimble on an enlarged scale illustrating the manner of drawing a thread against the edge of the cutting disc.

It is realized that sewing thimbles having means for severing thread have heretofore been developed but their commercial acceptance has been nil due to expense in manufacture, failure to perform the cutting function with ease and despatch and inability of the parts to prevent accidental engagement with the cutting edge. Replaceability of the cutting element has also been overlooked and since the shortcomings of thimbles heretofore produced are eliminated in the thread cutting thimble having our improvements therein, the same should be an important step forward in this particular art.

The form of thimble chosen for illustration comprises a conventional hollow body 10 having a cavity 12 therein for the reception of the end of the finger of the wearer. The top surface 14 of body 10 is substantially flat and there is an annular groove 16 formed around the outer periphery of body 10 immediately adjacent to and below surface 14. The cutting disc 18 has a sharpened, continuous annular edge 20 provided thereon and a central perforation 22 through

2

which passes screw 24 to threadingly engage a socket 26 in cap 28. This cap 28 should be formed of the same material as that from which body 10 is created in order to establish uniformity of appearance and the outer surface 30 of cap 28 should be convex to recede gently from its annular edge that lies just above the cutting edge 20 of disc 18.

The protecting element of the thimble is a specially formed coil spring 32 in the nature of a continuous annulus and having the convolutions in cross proximity. In other words, the coils of spring 32 are in contact throughout the length of the spring and no openings are present until a thread 34 is drawn against spring 32 to spread apart two adjacent convolutions of spring 32. This particular action is clearly illustrated in Fig. 3 where the thread or the like 34 is in contact with cutting edge 20 of disc 18 and spring 32 has been spread to receive the thread. The outside diameter of spring 32 is slightly greater than the diameter of disc 18 and the relation of these two parts is as shown in the sectional view of Fig. 2.

Spring 32 is nested in annular groove 16 and when a disc 18 is to be renewed, removal of screw 24, cap 28 and disc 18 will not cause spring 32 to jump from its operative position. The depth of groove 16 is not great enough to hold spring 32 out of contact with the lower surface of disc 18 and therefore, a full protective function is permitted. The entire length of cutting edge 20 is guarded by spring 32 and only upon the application of force to a thread 34 will spring 32 allow contact with the cutting edge.

Having thus described the invention what we claim as new and desire to secure by Letters Patent is:

1. A thimble comprising a hollow body; a cutting disc secured to the closed end of the body with a marginal edge thereof projecting radially beyond the outer surface of the body; and a coil spring surrounding the body in contacting relationship with the cutting disc below the marginal edge thereof, the outside diameter of the spring being greater than the diameter of the cutting disc.

2. A thimble comprising a hollow body; a cutting disc secured to the closed end of the body with a marginal edge thereof projecting radially beyond the outer surface of the body; and a coil spring surrounding the body in contacting relationship with the cutting disc below the marginal edge thereof, the outside diameter of the spring being greater than the diameter of the cutting

disc, the coils of said spring being in close proximity to completely cover one side of the disc, the coils being separable by the thread when drawn therebetween toward the edge of said disc.

3. A thimble comprising a hollow body; a cutting disc secured to the closed end of the body with a marginal edge thereof projecting radially beyond the outer surface of the body; and a coil spring surrounding the body immediately below the marginal edge of the cutting disc, said coil spring having an outside diameter slightly greater than the diameter of the cutting disc.

4. A thimble comprising a hollow body; a cutting disc secured to the closed end of the body with a marginal edge thereof projecting radially beyond the outer surface of the body; and a coil spring surrounding the body immediately below the marginal edge of the cutting disc, said coil spring having an outside diameter slightly greater than the diameter of the cutting disc, said body having an annular groove formed therein immediately below the projecting edge of the cutting disc to receive the inner portion of the coil spring.

5. A thimble comprising a hollow body; a cutting disc secured to the closed end of the body with a marginal edge thereof projecting radially beyond the outer surface of the body; and a coil spring surrounding the body immediately below the marginal edge of the cutting disc, the outside diameter of the spring being greater than the diameter of the cutting disc, said disc having a cap overlying the same to hold disc in position.

the diameter of the cap being slightly less than the diameter of the cutting disc.

6. A thimble comprising a hollow body; a cutting disc secured to the closed end of the body with a marginal edge thereof projecting radially beyond the outer surface of the body; a coil spring surrounding the body immediately below the marginal edge of the cutting disc, the outside diameter of the spring being greater than the diameter of the cutting disc; a cap overlying the disc; and a screw passing through the thimble body and the disc into threaded engagement with the cap whereby the cutting disc may be quickly removed and replaced, the upper and outer face of the cap being convex to recede from the cutting edge of the disc.
